United States Patent

Des. 238,756

Patented Feb. 10, 1976

238,756

PILL CONTAINER OR THE LIKE

James B. Swett, Barrington, R.I., assignor to Dart Industries Inc., Los Angeles, Calif.

Filed July 25, 1974, Ser. No. 491,888

Term of patent 14 years

Int. Cl. D3—01

U.S. Cl. D9—231

FIG. 1

FIG. 2

FIG. 3

FIG. 4

FIG. 5

FIG. 6

FIG. 7

FIG. 1 is a perspective view of a pill container or the like showing my new design as partially opened;

FIG. 2 is a front elevational view thereof as partially opened;

FIG. 3 is a back elevational view thereof as closed;

FIG. 4 is a front elevational view thereof as closed;

FIG. 5 is a right side elevational view thereof as closed;

FIG. 6 is a top plan view thereof; and

FIG. 7 is a bottom plan view thereof.

I claim:

The ornamental design for a pill container or the like, substantially as shown.
